UNITED STATES PATENT OFFICE

DE FOREST ANTHONY, OF FALL RIVER, AND BEATRICE M. STODDARD, OF DEDHAM, MASSACHUSETTS, ASSIGNORS TO DOROTHY DEWEY COMSTOCK, OF DEDHAM, MASSACHUSETTS, DOING BUSINESS AS THE KIDDIE-RHESTER CO.

PLAY PEN

Application filed June 8, 1929. Serial No. 369,299.

This invention relates to portable play pens for infants, and pertains more particularly to means for sustaining in upright position a foldable baby pen of the type disclosed in the 5 patent to Dorothy D. Comstock No. 1,463,459 dated July 31, 1923. The principal object of the invention is to provide a pen having bottom rails provided with bracing members movable outwardly in opposite directions to 10 support the extended pen against tilting, and movable in reverse direction to lie within the confines of the folded pen.

Further objects reside in the structural features of the devices hereinafter described 15 and illustrated in the accompanying drawings, in which:

Fig. 1 is a top view of an extended play pen equipped with the improved braces;

Fig. 2 is an enlarged corner detail of the 20 structure; and

Fig. 3 is a fragmentary end view of the pen shown in Fig. 1, to smaller scale.

As more fully described in said patent, the play pen may comprise a number of similar sections 11, 12, 13, 14, 15 and 16, each including longitudinal rails 17 at the top and bottom and connecting bars or spindles 18, the sections being pivotally interconnected as by 25 hinges 19 to form a rectangular enclosure 30 when extended, and to fold into parallel juxtaposed relation when the pen is collapsed. The abutting ends of the sections meeting at a separable corner of the extended pen may be secured by separable fastening members, as 35 at 20.

In accordance with the present invention, the bottom rail of each of the end sections is preferably formed with a longitudinal base slot 21 and with a slot 22 in the outer side of 40 the rail on each side of its center. The side slots intersect the slot 21 and may be separated from each other or may constitute a continuous opening, preferably terminating short of the rail ends. When the rail is made 45 of wood, a trough-shaped metal casing 23 is preferably applied over the bottom of the rail and secured by suitable fastening means, such as the tacks 24, so that the casing provides a bottom wall for the slot 21 and reinforces the 50 rail. A pair of aligned slots 25, in registra-

tion with the slot or slots 22, are provided in the outer side wall of the casing.

An elongate brace 26, preferably formed of a stout metal rod, is slidably received within each open end of the slot or groove 21, and said rods carry actuating knobs 27 having stems projecting through and guided by the registering side slots 22 and 25 of the rail and casing respectively. The knobs may be detachably affixed to the rods 26 by screw-threaded engagement in an obvious manner. Thus, the rods may be moved longitudinally of the rail to extend in opposite directions for supporting the extended pen in upright position, or to be entirely concealed within the 65 rail groove when the pen sections are folded together. The extent of movement of the rods is limited by the length of the casing slots 25.

The bracing members above described afford adequate support for the erected pen 70 when provided at the four corners of the pen, as shown in Fig. 1, so that it is substantially impossible for an infant to tip the pen sidewise; yet the braces are simple and economical to manufacture, easy to assemble in 75 the bottom rails of the pen sections, convenient to operate, and concealed in a non-interfering location when not in use. It will be understood, however, that structural details of the bracing devices may be varied to 80 suit particular purposes without departing from the essence of this invention as defined in the following claims.

We claim:

1. In combination with a pen of the type 85 described having foldable sections, bracing means for supporting the extended pen in upright position, comprising legs associated with some of the sections extendible longitudinally of said sections to bear upon the pen 90 supporting surface and movable inwardly thereof to lie substantially within the compass of the pen when the sections are folded together.

2. In combination with a foldable pen of 95 the type described having end sections provided with bottom rails, bracing means for supporting the extended pen in upright position, comprising legs associated with the opposite ends of said rails and movable out-

- wardly thereof to bear flatwise upon the pen supporting surface in line with their respective rails and inwardly thereof to lie substantially within the compass of the pen when the 5 sections are folded together.
3. In combination with a foldable pen of the type described having end sections provided with bottom rails, bracing means for supporting the extended pen in upright position, comprising legs associated with the opposite ends of said rails and slideable outwardly thereof to bear upon the pen supporting surface in line with their respective rails and inwardly thereof to lie within the compass of the pen when the sections are folded together.
4. In combination with the bottom rail of a foldable pen section, a bracing leg slideable longitudinally of the rail between its outer 10 and inner sides, means for guiding the leg during said movement, and means for limiting said movement in both directions whereby the leg may be slid outwardly to project a substantial distance beyond the end of the rail and inwardly past said end.
5. In a play pen comprising foldable sections provided with bottom rails, the bottom rail of one of said sections having a longitudinal groove in its base extending inwardly 15 from one of its ends, a bracing rod mounted for longitudinal movement in said groove, means for guiding the rod during said movement, a knob for moving the rod, and means for limiting said movement in both directions, whereby the rod may be slid outwardly to project a substantial distance beyond said rail end and inwardly past said end to lie substantially within the compass of the pen when the sections are folded together.
- 40 6. In a play pen comprising foldable sections provided with bottom rails, the bottom rail of one of said sections having a longitudinal groove in its base extending from end to end of the rail, individual bracing rods 20 mounted for longitudinal sliding movement in the opposite ends of said groove, said rail having longitudinal slots in its side, and a member attached to the respective rods and projecting outwardly through the respective slots, whereby the rods may be slid outwardly to project a substantial distance beyond the rail ends and inwardly past said ends by moving said projecting members, the extent of said movement being limited by the length of said slots.
- 60 7. In a play pen comprising foldable sections provided with bottom rails, the bottom rail of one of the sections having a longitudinal groove in its base extending from end to end of the rail, a reinforcing casing applied over the bottom and upon the sides of said rail, individual bracing rods mounted for independent longitudinal sliding movement in the opposite ends of said groove, said rail and casing having longitudinal slots in the

sides thereof, and knobs having stems affixed to said rods and projecting outwardly through the respective slots whereby the rods may be slid outwardly to project a substantial distance beyond the rail ends by moving the knobs and inwardly past said ends, the extent of said movement being limited by the length of the casing slots.

8. A foldable closure comprising frames defining the sides of the closure, opposite sides being provided with bottom rails having longitudinal grooves extending from end-to-end of the rails, individual bracing rods mounted for longitudinal movement disposed in the opposite ends of each of said grooves, and means associated with each of said rods for sliding the rod outwardly to project a substantial distance beyond the respective ends of the rail and inwardly to lie substantially within the compass of the closure when folded.

9. A foldable closure comprising frames defining the sides of the closure, the ends of the frames being pivoted together to define the corners, opposite sides of said closure having bottom rails provided with longitudinal grooves extending from end to end of the rails, individual bracing rods mounted for longitudinal movement in the opposite ends of said grooves, reenforcing casings secured to said rails, the casings having longitudinal slots communicating with the grooves in said rails, and means for sliding the rod outwardly to project a substantial distance beyond the rail ends and inwardly past said ends to lie substantially within the compass of the closure when folded, each of said means comprising a knob having a stem secured to the respective rods and projecting outwardly through the respective slots.

45 10. A foldable closure comprising frames defining the walls of a rectangular closure, the ends of the frames being pivoted together to define three corners of the closure, opposite end walls having bottom rails provided with longitudinal grooves extending from end to end of the rails, individual bracing rods mounted for longitudinal movement in the opposite ends of said grooves, reenforcing casings secured to said rails, said casings having longitudinal slots communicating with the grooves in said rails, and knobs having stem portions projecting through the slots and secured to said rods whereby the rods may be slid outwardly to project a substantial distance beyond the rail ends and inwardly past said ends, the extent of the movement being limited by the length of the casing slots.

Signed by us at Boston, Mass., this 16th day of May, 1929.

DE FOREST ANTHONY.
BEATRICE M. STODDARD.
